[57] CLAIM

The ornamental design for a rotary actuator for positioning magnetic head adjacent the surface of a magnetic disc, as shown.

DESCRIPTION

FIG. 1 is a perspective view of a rotary actuator showing our new design;

FIG. 2 is an elevational view showing the side opposite that shown in FIG. 1;

FIG. 3 is an elevational view showing the end of the rotary actuator as viewed from the right in FIG. 1;

FIG. 4 is a top plan view of the rotary actuator shown in FIG. 1; and

FIG. 5 is an elevational view showing the end of rotary actuator as viewed from the left in FIG. 1.

FIG. 6 is a perspective view of the side opposite that shown in FIG. 1.
